DESIGN FOR A CLOCK CASING

Henry Dreyfuss, New York, N. Y., assignor to
General Time Instruments Corporation, New
York, N. Y., a corporation of Delaware

Application November 19, 1938, Serial No. 81,241

Term of patent 14 years

To all whom it may concern:

Be it known that I, Henry Dreyfuss, a citizen
of the United States, residing in the city of New
York, in the county of New York and State of
New York, have invented a new, original, and
ornamental Design for a Clock Casing, of which
the following is a specification, reference being
had to the accompanying drawing, forming a part
thereof.

Fig. 1 is a front elevational view of a clock cas-
ing showing my new design; and
Fig. 2 is a side view thereof.

I claim:

The ornamental design for a clock casing, as
shown.

HENRY DREYFUSS.
